UNITED STATES PATENT OFFICE

115,489

DESIGN FOR A COMBINED CABINET AND END TABLE

Arthur A. Eisenberg, New York, N. Y., assignor
to National Silver Company, New York, N. Y.,
a corporation of New York

Application April 20, 1939, Serial No. 84,425

Term of patent 3½ years

To all whom it may concern:

Be it known that I, Arthur A. Eisenberg, a citizen of the United States, residing in the Borough of Manhattan, city, county, and State of New York, have invented a new, original, and ornamental Design for a Combined Cabinet and End Table, of which the following is a specification, reference being had to the accompanying drawing, forming a part thereof, in which:

Fig. 1 is a perspective view showing the front

and one side of a combined cabinet and end table embodying my new design, this view showing the cover in open position,

Fig. 2 is similar to Fig. 1 but shows the front and opposite side of the combined cabinet and end table and shows the cover in closed position.

I claim:

The ornamental design for a combined cabinet and end table, as shown.

ARTHUR A. EISENBERG.
